NAIL DISTRIBUTING AND LOADING APPARATUS

Edwin C. Eldred, Jr., Wenham, Mass., assignor to
United Shoe Machinery Corporation, Flemington, N. J., a corporation of New Jersey

Application December 17, 1948, Serial No. 65,849

5 Claims. (Cl. 1-39)

1

This invention relates to nail distributing and loading apparatus for use with a nail distributor such as are disclosed in an application for United States Letters Patent Serial No. 65,868, filed December 17, 1948 in the name of Wallace M. Cutler, et al.

The present invention consists in the novel features hereinafter described, reference being had to the accompanying drawings which illustrate one embodiment of the invention selected for purposes of illustration, and said invention being set forth in the following description and claims.

In the drawings.

Fig. 1 is a side view, partly broken away and partly in section, showing portions of loading mechanism of an illustrative heel attaching machine and portions of an illustrative associated nail distributor;

Fig. 2 is a longitudinal vertical section through the forward portion of the nail distributor illustrating the operation of mechanism for rendering a nail roll of the distributor ineffective;

Fig. 3 is a plan view showing portions of the loading mechanism of the heel attaching machine; and

Fig. 4 is a perspective view of a clip for closing off raceways of the distributor.

The illustrative nail distributor comprises a carrier 20 having a plurality of raceways 22 and nailways 24 down which nails 26 are fed in succession in response to vibration or oscillation of the carrier by mechanism such as disclosed in said application Serial No. 65,868. Journaled in the carrier 20 at the lower ends of the nailways 24 is a nail roll 28 having a plurality of passages 30, said roll when the distributor is at rest being arranged in the position shown in Fig. 1, the nails 26 extending through the passages of the roll and engaging a nail stop 32 mounted upon a front gate 34 which may be secured in different angularly adjusted positions to the carrier by a latch 36 (Fig. 1). The nail roll 28 is swung between a rest or nail receiving position shown in Fig. 1, in which the passages 30 of the roll are in alinement with the lower ends of the nailways 24, and a dumping position in which the roll is rotated counterclockwise from its position shown in said Fig. 1 to permit the nails to slide down said passages into conduits 38 (Fig. 2) formed between the main portion of the carrier and the front gate 34 which constitutes a front portion of the carrier.

Secured in slots 40 (Fig. 2) of the carrier 20 at the lower ends of the conduits 38 are tubes 42

2

the lower ends of which are housed in sleeves 44 (Fig. 1) having tapered lower ends inserted in passages 46 of a foot plate 48 below which is positioned a nail guiding unit 50 commonly referred to as a "beer mug." Upper ends of tubes 52 of the nail guiding unit 50 are in alinement with selected passages 46 of the foot plate 48 and the lower ends of the tubes 52 enter passages 54 of the foot plate, said passages 54 being arranged in a pattern identical with a pattern of nail passages 55 (Fig. 1) of a loader block 56 (Figs. 1 and 3) which is mounted upon an arm 58 and, during a portion of a cycle of operation of the heel attaching machine, dwells beneath the unit 50 to receive nails discharged head ends down from the nail roll 28.

When the heel attaching machine is at rest the loader block 56 is in a raised dash-line position shown in Fig. 1 ready to be swung during the first part of the next cycle of the machine, together with its arm 58, clockwise as shown in Fig. 3 or to the left as shown in Fig. 1, in response to rotation of a vertically splined shaft 60, the loader block when at the extreme end of said clockwise movement dwelling above a nailing die (not shown) of the heel attaching machine for a period of sufficient duration to enable it to discharge nails. When a nail retaining shutter 62 (Fig. 1) pivoted upon the under side of the loader block then positioned above the nailing die has been swung from beneath said block nails fall head ends down from the passage 55 of said block into the nail receiving passages (not shown) of the die, in which passages nail drivers (not shown) of the machine travel. The loader block carrying arm 58 is then swung counterclockwise as viewed in Fig. 3, back to its position shown in Fig. 3, or to the right as viewed in Fig. 1, in response to rotation of the shaft 60, to its dash line position shown in Fig. 1 and is thereafter lowered with said shaft and swung into a position in which the loader block 56 is arranged beneath the unit 50. When the loader block 56 arrives in its proper position below the unit 50 a spring actuated shutter 64 carried by said unit is released, with the result that nails then in said unit drop into the holes or passages 55 of the loader block. After a short dwell below the unit 50, the loader block arm 58 is swung to the left (Fig. 1) from beneath the unit 50 and is then raised with the shaft 60 to its dash line starting position shown in Fig. 1 where it remains at rest until the heel attaching machine starts its next cycle.

When the loader block carrying arm 58 is

swung clockwise as viewed in Fig. 3, or to the left as viewed in Fig. 1, from its rest position shown in these figures a plate 66 secured by screws 68 to said arm engages a latch 70 which is pivotally mounted upon a pin 72 carried by a rod 74 slidably mounted in a base 76 of the distributor and moves the rod to the left as viewed in Fig. 1 against the action of an initially loaded torsion spring 78 (Fig. 1) which will be referred to later. The rear end of the rod 74 is threaded into an arm 80 pivoted to the lower end of a lever 82 secured by a screw 84 to a pin 86 fulcrumed in the base 76 of the distributor. The upper end of the lever 82 has pivoted to it an arm 88 into which is threaded a rod 90. The lever 82 and accordingly the rod 74 are normally retained in their positions shown in Fig. 1 by the torsion spring 78 one end of which is secured to the pin 86 and the other end of which is secured to the base 76, movement of the rod under the action of the spring 86 being limited by the engagement of a shoulder 92 (Figs. 1 and 3) of the rod with the base 76.

The rear end of the rod 90 engages a cylindrical bore 94 of a block 96 which is secured by a screw 98 to the left end (as viewed from the front of the machine) of a pivot pin 100 journaled in the base 76 of the machine. The block 96 comprises a frusto-conical bore 102 extending into the cylindrical bore 94 and forming a shoulder 104 with said bore. Secured to the pivot pin 100 is a depressor 106 which is constructed and arranged to be engaged by a pawl 108 forming part of a one-revolution clutch (not shown) which is housed in a cam 110 (Figs. 1 and 2) mounted on a continuously rotated shaft 112. The block 96 is normally biased to a rest position against a stop 114 secured to the base 76, by a torsion spring 116 one end of which is secured to the pin 100 and the other end of which is secured to the base 76. When the rod 90 is moved to the right (Fig. 1) in response to movement of the loader block arm 58, the block 96 is rotated clockwise upon its pivot pin 100 against the action of the torsion spring 116 with the result that the pawl 108 actuated by a spring-pressed plunger (not shown) causes the clutch to be engaged and the cam to rotate 360° together with the shaft 112. The cam 110 has a front face 118 which during a portion of the cycle of operation of the machine is engaged by a roll 120 carried by the lower end of an arm 122 secured by a screw 124 to a pivot pin 126 fulcrumed in the base 76. Also secured to the pivot pin 126 is an upstanding arm 128 operatively connected by an adjustable rod 130 to an arm 132 secured to a left trunnion portion of the nail roll 28 which is fulcrumed in bores 134 of the carrier 20. When the machine is idle (Fig. 1) a screw 129 threaded into an arm 131 secured to the nail roll 28 is forced against a stop 135 (Fig. 2), secured to the carrier 20, by a spring 136 one end of which is attached to the arm 128 and the other end of which is fixed to the base 76. Secured to the pivot pin 100 is a housing 138 in which is mounted a spring-pressed plunger 140 constructed and arranged to override a shoulder 142 of the arm when the depressor 106 is swung clockwise (Fig. 1) away from the pawl 108, thereby insuring that the depressor shall not spring back into its position shown in Fig. 1 until the cam 110 has rotated past the depressor.

The latch 70 which is fulcrumed upon the pin 72 mounted upon the rod 74 is normally held in its position illustrated in Figs. 1 and 3, a pin 144

(Figs. 1 and 3) carried by the latch being forced against said rod under the action of a spring 146 which encircles the pin 72 and one end of which is attached to the rod and the other end of which engages an inner face of the latch. As above explained, during the first part of the cycle of operation of the heel attaching machine the loader block arm 58 is swung from its rest position clockwise as viewed in Fig. 3 or to the left as viewed in Fig. 1 to a position above the nailing die (not shown) of the machine. Such movement of the loader block arm 58 causes the rod 74 to slide to the left (Fig. 1) in the base 76 with the result that the rod 90 acting upon the shoulder 104 of the block 96 causes the pivot pin 100 and accordingly the depressor 106 to swing clockwise (Fig. 1) against the action of the torsion spring 116, the spring-pressed plunger 140 overriding the shoulder 142 of the arm 122 to hold the depressor against retraction. As above explained, movement of the depressor 106 away from the pawl 108 effects the engagement of the one-revolution clutch which causes the cam to move 360° with the shaft 112. As the rod 90 swings the block 96 clockwise (Fig. 1) it slides over the shoulder 104 of the block and through the frusto-conical opening 102, said rod immediately sliding back to a retracted position in the cylindrical bore 94 under the action of the torsion spring 116 until the shoulder 92 of the rod 74 engages the base 76.

As the loader block arm 58 swings counterclockwise as viewed in Fig. 3 back to its position shown in Fig. 3, or to the right as viewed in Fig. 1, preparatory to being lowered upon the shaft 60, the plate 66 overrides an outer surface 148 (Fig. 3) of the latch, causing said latch to swing upon the rod 74 against the action of the spring 146 to permit the plate to assume its position behind the latch. When the cam 110 rotates through one revolution it swings the nail roll 134 counterclockwise (Fig. 1) against the action of the spring 136 causing said roll to rotate from its nail receiving position shown in Fig. 1 in which its passages 30 are in alignment with the nailways 24, to its nail dumping position where it dwells, the nail roll then moving back under the action of the spring 136 to its initial position. As the arm 122 rotates clockwise as viewed in Fig. 1 the inclination of the shoulder 142 is such that the torsion spring 116 which continuously urges the pivot pin 100 clockwise (Fig. 1) overcomes the resistance of the spring-pressed plunger 140, causing it to be retracted and the depressor 106 carried by the pin to be moved to its pawl engaging position against the stop 114. The depressor 106 in engagement with the stop 114 is engaged by the pawl 108 just before the cam 110 completes one revolution thereby causing said clutch to be disengaged and the cam to come to rest.

In the use of the above apparatus it is necessary in operating upon shoes of different sizes and/or styles to substitute for the nails in the distributor nails of a different size or style. This entails stopping a nail drum (not shown) of the distributor and knocking nails from the raceways 22 and nailways 24 of the carrier 20 back into the nail drum and also removing the nails from the passages 30 of the nail roll 134 and from the passages 55 of the loader block 56 then in its rest position shown in dash lines in Fig. 1. To remove nails, and especially nails which are short, from the nail roll 28 and from the automatically operated loader block 56 of the above-

mentioned machine requires considerable time and usually results in many of the nails being spilled on the floor, such nails being wasted and likely to cause accidents.

In order to avoid having manually to remove nails of the discontinued size and style from the nail roll 28 and the loader block 56, there is pivotally mounted upon the pivot pin 86 at the left side of the distributor as viewed from the front, a lever or stop 150 (Figs. 1 and 2) having at its forward end a laterally extending handle 152. The lever 150 is normally arranged in its inactive dash line position shown in Fig. 2, a recess 154 of the lever at such time receiving a projecting detent 156 secured to the base 76 to retain the lever in its inactive or ineffective position. The balance of the lever 150 is such that when the lever is moved counterclockwise (Figs. 1 and 2) from its ineffective position and is thus released from its detent, it tends to swing counterclockwise.

When the heel attaching machine is at rest and one pair of shoes of a particular "run" are yet to be heeled and the next run of shoes requires nails of a different size or style, the operator swings the lever 150 counterclockwise from its inactive dash-line position, the lever after being released continuing to move counterclockwise until it engages a lug 158 secured to the upstanding arm 128 which is then in its position shown in Fig. 1. Also secured to the lever 128 is a lug 160 which, although it is shown as spaced from the lug 158, may be considered as part of the lug 158, the lugs 158, 160 being referred to as an angular lug. During the next cycle of operation of the machine the loader block 56 is swung to a position over the nailing die (not shown) causing, through the above described mechanism, the rod 90 to move the block 96 clockwise (Fig. 1) and the depressor 106 to move away from the pawl 108 of the one-revolution clutch with the result that said clutch is engaged to effect a 360° rotation of the cam 110 together with the constantly rotating shaft 112. Rotation of the cam 110 causes the lever 128 to swing rearward against the action of the spring 136. As the arm 128 swings rearward the lever 150, which is balanced to swing counterclockwise as viewed in Fig. 1, engages a forward edge of the lug 158. When the arm 128 has reached its rearward position where it dwells to enable the nails to be dumped from the passages 30 of the nail roll 28, the upper rear end of the lever engages the lug 158 and as the lever moves forward under the action of the spring 136 the lug 160 engages the rear end of the lever with the result that the lever stops when in the position shown in Fig. 2, the passages 30 of the nail roll when the lever is thus positioned being raised out of alignment with the nailways 24 so that nails on said nailways cannot enter the passages 30.

When there are two distributors used with the heel attaching machine the forward end of the locking lever 150 is pivotally connected by an adjustable rod 162 to a corresponding locking lever of an upper distributor (not shown), movement of the lever causing a corresponding movement of the locking lever of the upper distributor.

When the nails 26 have been collected in the nail drum (not shown) said drum is emptied and other nails which are to be used for the next run of shoes are dumped into the drum. The locking lever 150 is then swung back to its ineffective dash line position (Fig. 2) and is held in such

position by the detent thereby releasing the nail roll 28 which moves under the action of the spring 136 to its nail receiving position in which its passages are in alignment with the nailways, said position being determined by the engagement of the screw 129 on the arm 131 with the stop 135. The heel attaching machine and its distributor are then operated through two cycles without any work being presented, thereby supplying nails to the loader block 56 and to the nail roll 28.

The illustrative distributor has seven raceways 22 and nailways 24 but in operating upon certain types of work fewer than seven nails are driven at a time and it is therefore desirable to close one or more of the raceways 22. In distributors commonly in use the raceways 22 have formed in their bottoms holes (not shown) for receiving short nails which are placed in said holes and serve as abutments for stopping downward sliding movement of the nails along the raceways. Such a practice is undesirable because dirt and grease frequently fill up such holes and project into the paths of movement of the nails thus interfering with their progress down the raceways. Moreover the short nails serving as stops in the holes of the raceways merely stop the nails but do not deflect them from the raceways.

In order to close one or more of the raceways 22 of the carrier 20, which raceways may be described as bar shaped and as having grooves along which nails travel, there is provided a metal stop or clip 164 which has flexible depending legs or sides with flaring lower ends, said legs when forced onto one of the raceways being constructed and arranged to spring over or straddle the sides of the raceway into its binding position shown in Figs. 1 and 2. The rear upper end of the stop 164 has a V-shaped ramp 168 which is constructed and arranged when the stop straddles one of the raceways, as shown in Fig. 2, to fit into said raceway at an angle to the lengthwise dimension of the raceway, thereby causing nails to be deflected out of the raceways, such nails falling through recesses (not shown) between the raceways and back into the nail drum. At the forward upper portion of the stop 164 is an upwardly extending flange or handle 170 for facilitating the removal of the clip from one of the raceways.

The nail stop or clip 164 illustrated in Fig. 4 is disclosed and claimed in a divisional application Serial No. 177,229, filed August 2, 1950.

Having described the invention, what I claim as new and desire to secure by Letters Patent of the United States is:

1. In a nail distributing and loading apparatus, nailways along which nails are fed, a plurality of conduits, a member for receiving nails from the nailways and transferring them to the conduits, mechanism for operating said member, and manually operated means movable to a predetermined position to render said mechanism and accordingly said member ineffective to receive nails from the nailways after said member has transferred a load of nails to the conduits.

2. In a nail distributing and loading apparatus, nailways along which nails are fed, nail guides, a member for receiving nails from said nailways and delivering them to said guides, a loader block for receiving nails from said guides, means movable in response to movement of the loader block for operating said member to cause nails to be delivered to said guides and into the loader block, and manually operated mechanism for stopping

said means in a predetermined position to prevent feeding of nails from the nailways to the guides.

3. In a nail distributing and loading apparatus, a nail roll movable between nail receiving and nail dumping positions, a cam, a spring, means which is operated by the cam to move the roll from nail receiving position to nail dumping position and which is operated by the spring to move the roll from nail dumping position to nail receiving position, and a manually actuated lever movable into an operative position, said lever being constructed and arranged to be engaged by said means to prevent the roll from being moved under the action of said spring to its nail receiving position.

4. In a nail distributor, a plurality of nailways, a nail roll having a plurality of passages, means for rocking said nail roll between a nail receiving position in which the passages are in alinement with the nailways and a nail dumping position from which nails are dumped from the nail rolls, and a manually operated stop movable from an ineffective to an effective position for preventing movement of the nail roll to said nail receiving position.

5. In a nail distributor, a plurality of nailways, a nail roll having a plurality of passages, means for rocking said nail roll between a nail receiving position in which the passages are in alinement with the nailways and a nail dumping position from which nails are dumped from the nail roll, a manually operated stop movable from an ineffective to an effective position for preventing movement of the nail roll to its nail receiving position, and a detent for holding the stop in its ineffective position.
